TYPE BED BEARER

Application filed September 12, 1931. Serial No. 562,444.

- This invention relates to improvements in bed bearers for printing presses of the type having an impression cylinder and a cooperating, reciprocable type bed.
- Important objects of the invention are, to provide type bed bearers designed to improve the quality of the printing and prevent injury to the type; to provide such bearers having uninterrupted bearing surfaces insuring equalized distribution of wear therealong; to provide such bearers designed to prevent yielding thereof under the pressure of the impression cylinder and consequent uneven printing; and to provide such bearers with mountings therefor designed to facilitate the installation of the bearers between the type bed and the impression cylinder. Other objects of the invention will appear hereinafter.
- In the drawings, Fig. 1 is a diagrammatic longitudinal section taken through a portion of a printing press and showing an impression cylinder and a type bed equipped with our improved bearers;
- Fig. 2 a view similar to Fig. 1, showing the manner of installing the bearers;
- Fig. 3 an enlarged detail sectional view showing one of the design features facilitating the installation of the bearers;
- Fig. 4 a plan view of a portion of the type bed with the bearers mounted thereon together with a type form set-up;
- Fig. 5 an enlarged cross section taken on the line 5—5 of Fig. 1;
- Fig. 6 a section taken on the line 6—6 of Fig. 5;
- Fig. 7 an enlarged section taken on the line 7—7 of Fig. 1;
- Fig. 8 a view similar to Fig. 5, showing a slight modification of the bearer bar mounting.
- In a printing press of the bed and cylinder type, the bearers form track rails for the impression cylinder, and are intended to limit the printing depression of the cylinder and preserve a uniform relationship between the cylinder and the type forms during a printing operation. Heretofore it has been customary to attach the bearers to the type bed by screws inserted downward through
- holes opening through the top surfaces of bearers. These holes reduce the bearing area at points along the bearers and consequently the bearers are more rapidly worn down at these points. The screw holes also weaken the bearers and often cause them to crack or break. It has been found that the uneven wearing down of the bearers causes uneven printing and injury to the type as it permits the impression cylinder to depress slightly farther at the worn points. A wear down of as little as a thousandth of an inch is sometimes sufficient to mar the printing; and wear of several thousandths of an inch will often cause injury to the type also. The present improved bearers have been devised to prevent this objectionable wear and satisfy all of the fine practical requirements of the service.
- Referring to Figs. 1 to 7 inclusive, the bearers are two straight metal bars 1 of square or rectangular cross section and each having a flat, smooth, uninterrupted bearing face 2 and a flat, smooth under face 3 to rest upon the flat upper surface of the type bed, designated B. Each bar has the usual cleft 4 at its leading end rendering it yieldable and springy under the impression cylinder C. A description of one bar will suffice for both. At its under side the bar has a row of vertical sockets 5 equally spaced along the bar and centered transversely thereof. The row of sockets begins at a point spaced a material distance from the leading end of the bar and extends to a point adjacent the opposite end of the bar. In the present instance there are four sockets but the number may be varied. Each socket is cylindrical and terminates materially beneath the bearing surface 2. At one of its lateral or side faces, preferably the inner one, the bar has a row of transverse threaded apertures 6 each opening tangentially into one of the sockets 5 and terminating materially short of the opposite lateral face of the bar. These threaded apertures are spaced only slightly above the under face of the bar. Screwed into each aperture is a setscrew 7 having a socket in its outer end.

to receive a tool for screwing it, and a conical inner end 8.

At an intermediate point one of the bars has a flat, approximately rectangular recess 9 in its inner lateral face. This recess opens through the underface of the bar but terminates below the upper face 2. A clamping plate 10 is adapted to fit in the recess with its lower edge slightly above the lower face of the bar to clear the type bed. For supporting and adjusting the clamping plate, there is a screw 11 screwed into a threaded aperture 12 extending from the recess to the opposite face of the bar and swiveled to the plate, as at 13. This screw also has a tool-receiving socket in its outer end.

In its opposite side margins the type bed B has two parallel rows of threaded apertures 14 whose spacing corresponds to that of the sockets 5. In each aperture 14 is a stud 15 having a threaded shank 16 screwed into the aperture, and a head 17 projecting from the upper surface of the type bed and forming a shoulder 18 at its juncture with the shank positively limiting the screwing in of the shank and binding against the bed to prevent unscrewing. The stud head has a circumferential groove 19 transversely curved in cross section and, above and below said groove, the head has cylindrical portions 20 and 21 of a diameter for entering the bar sockets 5 and fitting them closely. The height of the stud heads is less than the depth of said sockets.

The bearers are designed in the present instance for mounting upon a standard Kelly press without any alterations therein and without demounting the impression cylinder. In the press, the impression cylinder in non-printing position has a definite separation from the bed and from the bearers, which only slightly exceeds the depth of the bearers. It is required that the leading end portions of the bearers be mounted in this limited separation space and our bearers have been designed to provide for this installation without difficulty and at the same time afford the advantage of uninterrupted bearing surfaces. In the installation of each bar its leading end is inserted under the cylinder, tilted as shown in Fig. 2, and rocked down to fit the sockets 5 over the stud head. There is a correlation of the height of the stud heads, the location and proportions of the stud grooves 19, and the separation of the cylinder from the type bed which enables the installation of the bars in the limited space available, and without a sacrifice of strength in the bar mountings. The height of the stud heads is, in the present instance, approximately seven-sixteenths of an inch and the grooves 19 are located only slightly below the tops of the heads. The bars are then placeable over the stud heads and under the cylinder and are

rockable downward over the stud heads. The grooves 19 provide clearance for an edge of the tilted sockets 5, as shown in Fig. 3, and enable the sockets, formed for closely fitting the stud head, to be pulled down over the latter.

Having placed the bars over the stud heads, the setscrews 7 are screwed in to engage the heads and fasten down the bars. The grooves 19 and the setscrews are formed and disposed to cooperate for this purpose. The center line of the setscrew is spaced above the under face of the bar equally with the space between the center line of the groove and the face of the type bed. The center line of the setscrew is also transversely spaced slightly from the bottom of the groove so that the point of the setscrew will not engage the groove. When the setscrew is tightened the conical end thereof makes a camming side-wise engagement with the stud groove which reacts to pull the bar down closely upon the type bed and firmly hold it there. If the bed is not absolutely flat the bars will be warped slightly by said fastening means into close engagement with the bed. It is important that the bars follow the surface of the bed closely in order to support the impression cylinder in proper relation to the type forms which are also supported by the bed. The stud-receiving sockets entirely surround the studs and fit them closely to positively hold the bearers against lateral displacement in any direction on the bed and maintain them in accurate relation to the impression cylinder.

In Fig. 8 the setscrew is shown in a position with its center line spaced above the under face of the bearer bar a distance slightly exceeding the normal space between the center of the stud groove and the type bed. This enables the setscrew to compensate for slight inequalities or irregularities and insures the pulling of the bearer bar tight against the type bed.

It will be seen that we have provided bearers having the desired uninterrupted bearing surfaces with equalized distribution of wear, that the bearers are strong, durable and unyielding under the cylinder pressure, that effective means are provided for drawing the bars accurately into place upon the bed, and that the bearers are at the same time capable of easy installation.

In Fig. 4 a type form 22 is shown mounted upon the type bed between the bearer bars and held in a frame 23 by suitable quoins 24. The clamping plate 10 is forced by its screw 11 against the frame 23 to press the latter against a spacing strip 25 interposed between the frame and the opposite bearer bar.

What we claim is:

1. In a printing press including an impression cylinder and a cooperating relatively reciprocable type bed, a bearer bar disposed

- upon the bed and having sockets spaced therealong in its under face and terminating short of the bearing face of the bar, and threaded apertures in a lateral face of the 5 bar opening into said sockets; studs having threaded shanks screwed into the type bed and projecting heads snugly fitting in said sockets and each having a circumferential groove and a shoulder positively limiting the 10 screwing of the stud shank into the bed to locate said groove in a definite position spaced from the bed, the walls of the sockets surrounding said studs to hold the bar against lateral displacement in any direction; and 15 set screws screwed into said threaded apertures and having tapered inner ends tangentially engaging the grooved stud heads and cooperating with the grooves to hold the bar close against the bed.
- 20 2. In a printing press including an impression cylinder and a cooperating relatively reciprocable type bed and wherein the cylinder has a limited separation from the bed, a pair of bearer bars disposed upon the bed 25 between the bed and cylinder and having sockets spaced along them in their under sides and terminating short of the bearing faces of the bars and threaded apertures in a lateral face of each bar opening tangentially 30 into said sockets; studs having threaded shanks screwed into the type bed and projecting heads snugly fitting in the sockets of the bars and each having a circumferential groove, the walls of the sockets surrounding 35 said studs to hold the bar against lateral displacement in any direction; means positively limiting the screwing of the stud shanks into the bed to locate the stud grooves in positions definitely spaced from the bed; and 40 setscrews screwed into said threaded apertures and having tapered inner ends tangentially engaging the grooved stud heads and cooperating with the grooves to hold the bar close against the bed, the projecting length 45 of the stud heads being correlated with the limited separation of the cylinder from the bed to permit mounting of the bars by tilting them, inserting their ends under the cylinder and rocking them into position over the 50 stud heads.
3. In a printing press including an impression cylinder and a cooperating relatively reciprocable type bed, a bearer bar disposed upon the bed and having sockets spaced therealong in its under face and terminating short of the bearing face of the bar, and threaded 55 apertures in a lateral face of the bar opening into said sockets; studs projecting from the type bed, snugly fitting in said sockets and each having a concavity in its periphery, 60 the walls of the sockets surrounding said studs to hold the bar against lateral displacement in any direction; and setscrews screwed into said threaded apertures and having tapered inner ends making tangential wedging engagement with the studs in the concavities thereof to hold the bar close against the bed.
4. In a printing press, a type bed, a bearer bar disposed upon the bed and having sockets in its under face terminating short of the upper face of the bar; studs projecting from the bed and snugly fitting in said sockets, the walls of the sockets surrounding said studs to hold the bar against lateral displacement in any direction; and releasable locking means between the bar and studs holding the bar close against the bed.
5. In a printing press including an impression cylinder and a cooperating relatively reciprocable type bed and wherein there is a limited normal clearance between the bed and cylinder, a bearer bar disposed upon the bed between the latter and the cylinder and having longitudinally spaced sockets in its under face; fixed studs projecting from the bed and fitting in said sockets, the walls of the sockets surrounding the studs to hold the bar against lateral displacement in any direction; and releasable locking means between said studs and the bar for holding the bar closely against the bed, the projecting length of the studs and the clearance between the bed and cylinder being correlated to permit mounting of the bar by tilting it, inserting an end thereof through the clearance space and rocking the bar into position over the studs.
6. A bearer for the type bed of a press comprising a bar having longitudinally spaced sockets in its under face and terminating short of its bearer face and threaded apertures in a lateral face of the bar opening tangentially into said sockets; studs having threaded shanks for screwing into apertures of the type bed and heads for fitting in said sockets and each having a circumferential groove, the walls of the sockets surrounding the studs to hold the bar against lateral displacement in any direction; and setscrews for screwing into the threaded apertures of the bar having tapered ends tangentially engageable in the grooves of the stud heads and cooperable therewith for drawing the bar close against the type bed when the setscrews are tightened.
- In testimony whereof we hereunto affix our signatures this 21st day of August, 1931.
